UNITED STATES PATENT OFFICE

110,862

DESIGN FOR A PLATE FOR SUPPORTING BUS BARS IN A BUS DUCT SYSTEM

William H. Frank, Detroit, Mich.

Application July 3, 1937, Serial No. 70,247

Term of patent 14 years

To all whom it may concern:

Be it known that I, William H. Frank, a citizen of the United States and a resident of Detroit, Michigan, have invented a new, original, and ornamental Design for a Plate for Supporting Bus Bars in a Bus Duct System, of which the following is a specification, reference being had therein to the accompanying drawings.

Fig. 1 is a top plan view of the plate for supporting bus bars in a bus duct system showing my new design.

Fig. 2 is a horizontal mid-section therethrough.

Fig. 3 is an enlarged perspective view in which only one of the sections is shown in full lines, bringing out the depths of the grooves the remaining portions being indicated in dotted lines.

What I claim is:

The ornamental design for a plate for supporting bus bars in a bus duct system, substantially as shown.

WILLIAM H. FRANK.
